PANEL AND PANEL COVER, ESPECIALLY
FOR RAILWAY CARS

Michael Watter, Philadelphia, Pa., assignor to
The Budd Company, Philadelphia, Pa., a cor-
poration of Pennsylvania

Application November 1, 1948, Serial No. 57,683

8 Claims. (Cl. 105—401)

1

The invention relates to panels of sheet material and also to cover or trim sheathing therefor. More particularly, the invention relates to a shear panel structurally secured to the outside of posts or other transverse frame members of railway car and similar vehicle bodies.

An object of the invention is a panel which combines strength and stiffness with light weight. Another object of the invention is a panel which, if used without fluted cover or trim sheathing, gives to a marked degree an appearance similar to that of a panel provided with such sheathing. Further objects of the invention are simple and economical manufacture of panel and trim sheathing, simplicity of securing of the trim sheathing to the panel, and reduction of the number of parts as compared with similar known structures.

With these and other objects in view, the invention contemplates a shape of the nodes or corrugations on the panel and a mating formation of cover sheathing such that the latter is removably held along its margins by the sides of the nodes or corrugations.

The above briefly outlined and further objects, advantages and features of the invention will be found in the following description of several embodiments illustrated in the attached drawing.

In the drawing:

Figure 1 is a fragmentary perspective side elevation, partially in transverse section, of the lower portion of side wall and adjoining under-frame side sill of a sheet metal railway car;

Figure 2 is a fragmentary section, on a larger scale, along line 2—2 of Figure 1; and

Figures 3, 4 and 5 are fragmentary sections similar to Figure 2 but each illustrating a different embodiment.

The railway car body shown fragmentarily in Figures 1 and 2 comprises a plurality of longitudinally spaced upright posts 10, one being shown in Figures 1 and 2 and another being visible in Figure 2. The posts have their lower ends interconnected by a bottom sill or chord comprising a Z-section 11 and a gusset plate 12. The outer arms of section 11 and plate 12 are overlappingly secured to each other and to the web of under-frame side sill 13. In the region of window openings 14 (only one opening is shown fragmentarily in the drawings), the posts are interconnected by a structural dead light panel 15 and window sill members 16. The construction described so far is known.

A shear panel 17 and a belt rail 18 structurally interconnect posts 10, gusset plate 12, dead light

panel 15, and window sill members 16. Shear panel 17 has longitudinally extending nodes or corrugations 19. The individual width of the nodes is several times smaller than the space between successive nodes. Each node 19 has a top wall 20 and side walls 21 forming together an inwardly facing channel section. Top walls 20 are profiled to give the appearance of narrow trim or molding strips. The side walls 21 of each node converge inwardly toward each other so as to present undercut surfaces adapted to retain removable cover plates or strips 22.

Each elongated cover plate 22 is in the form of a narrow long channel with a concave, fluted or otherwise transversely arched web 23 and marginal flanges 24. The edges of the flanges 24 are curled in at 25. Plates 22 form together a trim or cover sheathing for the shear panel 17.

Plates 22 consist of resilient material, such as thin cold rolled austenitic stainless sheet steel. The thickness may be 0.02". Their width 26 and the angles between their flanges 24 and their webs 23 are such that each plate can be sprung into place between the side walls 21 of successive nodes 19 and will be held in place by the resiliency of the plate as well as by the engagement of the flanges 24 with the side walls 21. The width of the flanges 24 is such that the curled in edges 25 nest in the angle between the side walls 24 and the adjoining main portions of panel 17.

The uppermost node 19 is formed as part of the belt rail 18. The lowermost node 19 serves for retaining the upper flange of rub rail 28. The lower flange of rub rail 28, together with the upper margin of skirt molding 29, is secured to sill 13 by blind rivets 30, screws or the like, and the lower margin of skirt molding 29 is welded to the inwardly directed lower flange of rail 13. This securing of belt rail and the securing of the rub rail form part of the subject matter of the application of Albert G. Dean, Serial No. 57,796, filed simultaneously herewith, for "Marginal Rail for Cover Strip Retaining Panels, Especially for Railway Car."

In the construction illustrated in Figure 3, the shear panel 31 consists of a plate 32 and welded-on channel sections 33. The cross section of the channel sections 33 is substantially the same as that of the nodes 19 in the first embodiment. Flanges 34 on node members 33 serve for the attachment to panel 31. The node members 33 together with the panel 31 form closed box sections thereby increasing the stiffness and strength of the panel as compared with the construction of Figures 1 and 2. The cover plates

55

35 are also substantially identical with the cover plates 22 illustrated in Figure 2 except that the edges of the flanges or arms 36 are continued by narrow flanges 37 directed toward each other and engaging the flanges 34 of node members 33.

In Figure 4, the shear panel consists, as in Figure 3, of a flat plate 38 and welded-on flanged channel sections 39 forming the nodes. The top wall of the nodes 39 is convex. The cover plates 40 have narrow flanges 41 along their edges, which extend at an angle to the flanges of the channel sections or nodes 39 for holding the plates 40 at the proper distance from the panel 38.

Figure 5 differs from the preceding embodiments in that the side walls 42 of the nodes 43 have convex or shallow V-section and that the flanges 44 of the cover plates 45 are correspondingly shaped so as to nest in the hollows of walls 42. As in Figures 3 and 4, the nodes 43 are formed on separately made sections welded to a flat plate 46.

The nodes perform several functions. In the first place, they increase the strength and stiffness of the shear panel; in the second place, they form means for the attachment of the cover plates; and in the third place, they give a vehicle an appearance when run without cover strips which is to a considerable extent similar to the appearance of cars provided with the fluted sheathing.

The shear panel, whether the nodes are formed on it per Figures 1 or 2, or constituted by separately formed welded-on members per Figures 3, 4 and 5, can be easily and economically manufactured. The cover plates also are easy and economical to manufacture. They can easily be installed or removed and can easily be replaced in case of damage to one or several of them without requiring removal of adjoining strips which were not damaged.

The longitudinal members shown in the drawing extend over a large part of or over the entire vehicle length. The parts of the body which are not illustrated may be of any known construction.

The invention is susceptible to further modifications. For instance, it will be understood that the different illustrated shapes of the cover plates as well as the different shapes of the walls of the nodes may be employed for shear panels provided with separately manufactured nodes per Figures 3, 4 and 5 as well as for corrugated panels per Figures 1 and 2. It should, therefore, be understood that such and other modifications may be employed without departing from the spirit and scope of the invention.

What is claimed is:

1. In a railway car or similar vehicle body; a plurality of longitudinally spaced structural members, such as upright side wall posts, extending transversely to the longitudinal direction of the body; a longitudinally extending sheet metal shear panel structurally interconnecting said members; a plurality of sheet metal nodes provided on and integral with said panel and projecting beyond the outer surface thereof, said nodes reinforcing said panel; said nodes extending longitudinally and being arranged parallel to and with spacing between each other; said nodes being of channel section with a top wall spaced from the panel and with side walls, these side walls having outer portions projecting laterally beyond portions nearer to the surface of the panel; said projecting outer portions constituting retaining means for outer trim sheathing.

2. In a body for railway cars and similar vehicles, comprising longitudinally spaced vertical posts separated in the upper regions by window openings and interconnected below the window openings on the outside by a shear panel, the combination with a plurality of longitudinally-extending vertically-spaced channel sections, the open sides of said channel sections facing said shear panel, lateral flanges on said channel sections being overlappingly secured throughout their length to said shear panel, said channel sections and panel forming closed box-sectional reinforcements, said channel sections having side walls which at least over part of their width converge toward each other from the outside toward the shear panel, the side walls of each two successive channel sections forming a dovetail section adapted for removably retaining a trim panel having its margins shaped matingly to said side walls.

3. In a body for railway cars or other vehicles, a wall provided with nodes extending parallel to and being transversely spaced from each other, undercut side wall portions on said nodes, a resilient cover strip of sheet material having flanges along opposite margins shaped to fit into said undercut portions, the width of the cover strip being greater than the space between successive nodes so as to permit the cover strip to be sprung into place to be held resiliently between the side walls of successive nodes and to engage with its flanges the undercut portions of the side walls to be retained by them.

4. In a body for railway cars or other vehicles, a wall provided with nodes extending parallel to and being transversely spaced from each other, shallow channel-section side walls on said nodes, the open sides of the channel sections facing toward the adjacent nodes, resilient cover strips of sheet material having flanges along opposite margins shaped matingly to said side walls interconnected by a web, the resiliency of said cover strips being such as to permit transverse bending of said webs, the width of each cover strip being, prior to its attachment to said nodes, slightly greater than the space between successive nodes so as to permit the cover strip to be sprung into place and to be held by resilient engagement of its flanges and said side walls.

5. In a body for railway cars or other vehicles, a wall provided with nodes extending parallel to and being transversely spaced from each other, resilient cover strips of sheet material having flanges along opposite margins interconnected by a web, the resiliency of said cover strips being such as to permit transverse bending of said webs, the width of the cover strips being such as to permit their insertion by transversely bending them between successive nodes, the sides of said nodes and the margins of said strips being provided with mutually engaging portions so that the strips are held in place by said nodes; the tops of said nodes constituting trim moldings filling the space between successive cover strips.

6. A sheathing member for railway cars and other structures, in the form of an elongated parallel-sided plate, said plate consisting of thin resilient sheet material having a web curved in cross-section at least over part of its width, and having flanges along its parallel sides, said flanges diverging at least over part of their width in the direction away from said web for fitting between and engaging a matingly shaped pair of surfaces provided on a supporting structure when said member is sprung into place between

said surfaces of a supporting structure, said flanges having extensions directed toward the middle of the sheathing member and being adapted for engaging said supporting structure so as to accurately determine the position of said web relative to said supporting structure.

7. An elongated trim sheathing plate for railway cars and other structures, having a resilient web with parallel margins and angle-section flanges along said margins, said flanges being formed for engagement with matingly shaped nodes on a supporting structure, and the resiliency of said web being such as to permit, by transversely bending it, the spring of said plate into position between successive nodes.

8. In a railway car or similar vehicle body of the type comprising: a plurality of longitudinally spaced structural members extending transversely to the longitudinal direction of said body; a longitudinally extending shear panel structurally interconnecting said members; a plurality of nodes provided on said panel and projecting beyond the outer surface thereof; said nodes being of channel section with a bottom wall and side walls, said nodes extending longitudinally and being arranged parallel to and with spacing between each other; the combination with the features of adjacent nodes having their side walls

which face each other arranged in planes diverging from the outside toward the inside; trim members fitting between said nodes, said members each having a resilient web and marginal flanges diverging in the direction away from the web, said flanges engaging said side walls for the retention of the members by said side walls, and the edges of said flanges being directed toward the middle of the respective member for engagement with the portion of the shear panel adjoining said side walls thereby holding said webs at the desired distance from said panel.
